US00D993057S

(12) **United States Design Patent** (10) Patent No.: **US D993,057 S**
Barbedette et al. (45) Date of Patent: ** Jul. 25, 2023

(54) **SCALE**

(71) Applicant: **WITHINGS**, Issy-les-Moulineaux (FR)

(72) Inventors: **Thibaut Barbedette**, Paris (FR);
Arthur Richard, Paris (FR); **Thomas**
Droze, Paris (FR)

(**) Term: **15 Years**

(21) Appl. No.: **35/514,516**

(22) Filed: **Dec. 27, 2021**

(80) **Hague Agreement Data**

Int. Filing Date: **Dec. 27, 2021**

Int. Reg. No.: **DM/218579**

Int. Reg. Date: **Dec. 27, 2021**

Int. Reg. Pub. Date: **Jul. 1, 2022**

(51) **LOC (14) Cl.** 10-04

(52) **U.S. Cl.**

USPC **D10/92**

(57) **CLAIM**

The ornamental design for a scale, as shown and described.

DESCRIPTION

1. Scale

2. Scale

3. Scale

1.1 : Top

1.2 : Bottom

1.3 : Left

1.4 : Right

1.5 : Front

1.6 : Back

1.7 : Perspective

1.8 : Perspective

1.9 : Left

1.10 : Front

1.11 : Back

1.12 : Perspective

1.13 : Perspective

2.1 : Top

2.2 : Bottom

2.3 : Left

2.4 : Right

2.5 : Front

2.6 : Back

2.7 : Perspective

2.8 : Perspective

2.9 : Left

2.10 : Front

2.11 : Back

2.12 : Perspective

2.13 : Perspective

3.1 : Top

3.2 : Bottom

3.3 : Left

3.4 : Right

3.5 : Front

3.6 : Back

3.7 : Perspective

3.8 : Perspective

3.9 : Left

3.10 : Front

3.11 : Back

3.12 : Perspective

3.13 : Perspective

The broken line showing of structural features is included

for the purpose of illustrating non-claimed subject matter

and forms no part of the claimed design.

1 Claim, 39 Drawing Sheets
